UNITED STATES PATENT OFFICE.

ALBERT WATERMAN AND RUDOLF WATERMAN, OF NEW YORK, N. Y.

GAGE AND MARKER FOR GARMENTS.

SPECIFICATION forming part of Letters Patent No. 781,478, dated January 31, 1905.

Application filed August 5, 1904. Serial No. 219,660.

To all whom it may concern:

Be it known that we, ALBERT WATERMAN, a citizen of the United States, and RUDOLF WATERMAN, a subject of the Emperor of Austria-Hungary, both residents of the city of New York, borough of Manhattan, in the county and State of New York, have invented a new and Improved Gage and Marker for Garments, of which the following is a full, clear, and exact description.

The object of our invention is to improve upon and simplify the construction of the gage and marker for garments for which Letters Patent were granted to Albert Waterman July 19, 1904, No. 765,529, and to so construct the device that the marking-arm will be capable of vertical, horizontal, and swinging adjustment, thus enabling the said arm to be accommodated to different characters of work, and especially for marking skirts in such manner that a hem may be evenly turned up at the bottom of the skirt, having either a plain or a fancy finish, and to render the adjustment such that the marking-chalk will be under the complete control of the operator.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of the device, illustrating its application. Fig. 2 is an enlarged horizontal section taken just above the marking-arm, the marking-arm being shown in plan view. Fig. 3 is a section taken practically on the line 3-3 of Fig. 2. Fig. 4 is a perspective view of a portion of the device, illustrating a slight departure in its construction. Fig. 5 is a horizontal section through another type of the device, the section being taken practically on the line 5-5 of Fig. 6. Fig. 6 is a vertical section taken substantially on the

line 6-6 of Fig. 5, and Fig. 7 is a horizontal section taken practically on the line 7-7 of Fig. 1.

A represents a platform upon which the person stands whose garment is to be marked or gaged and taken up, for example. This platform is supported by a pedestal 10, circular in cross-section and provided, preferably, with a series of outspreading legs 11, having attached casters 12. A block 13 is mounted to have rotary and guided movement on the pedestal, and said block has an offset at one side provided with a polygonal slot 14 and a thumbscrew 15, leading into the slot. In connection with the rotating block an L-shaped measuring-bar B is employed, the lower horizontal lug or arm b whereof is passed through the slot 14 in the block 13 and is secured by the thumbscrew 15, while the other member or arm b' extends upward and is provided with a scale 16 in inches and fractions of the same.

A sleeve 17 is mounted to slide on the scale-arm b' of the measuring-bar B, the sleeve being held in any adjusted position by the setscrew 18 or its equivalent. A hinge 19 has one leaf secured to the sleeve 17, the other leaf of the hinge being attached to a guide-arm C near its inner end, the said guide-arm C comprising upper and lower parallel bars 20 and 21, connected by vertical end bars 22.

A shoe C' is mounted to slide in the space between the upper and lower bars 20 and 21, being guided by the said bars of the said guide-arm, and the said shoe is prevented from dropping from the guide-arm by means of flanges 23 extending from the top and the bottom at both sides of the said guide-arm, as is shown in Fig. 3. This shoe C' carries a bolt 24, which extends outward from the said shoe, and a bearing 25 is attached to the hinge 19, and said bearing 25 extends outward between the members 20 and 21 of the guide-arm C, as is shown in Fig. 1.

A marking-arm 26 is also employed, and this marking-arm under the construction shown in Figs. 1, 2, and 3 is hollow and rectangular in cross-section, has free movement

in the bearing 25, and is provided at its outer end portion with a series of apertures 27, through any one of which the screw 24 is passed, and the screw is held to the marking-arm by means of nuts 28 and 29, as is shown in Fig. 3. It will be observed that the marking-arm 26 under this arrangement has perfectly free movement on the guide-arm C and that the extent to which said movement can take place is regulated by the position of the bolt 24 on the marking-arm. It will be further observed that in addition to the upward adjustment of the marking-arm brought about by the adjustment of the sleeve 17 the marking-arm has the horizontal movement above referred to, and in addition to these two movements the marking-arm has also a swinging movement or can be carried more or less at an angle to the article to be marked, so as to make the impression more or less pronounced or fine. Thus it will be observed that the manipulation of the marking-arm is entirely under the control of the operator. The inner end of the marking-arm 26 is provided with series of tongues 30, and the marking-chalk 31 is held between these tongues, being clamped in position by a slip-collar 32, and a follower 33, located in the said marking-arm, provided with an outwardly-extending arm 34, may be utilized to feed the chalk outward as it becomes worn.

In Fig. 4 we have illustrated a slight departure from the construction shown in Figs. 1, 2, and 3. This departure consists in attaching an arm 35 to the sleeve 17 and forming a vertical socket 36 at the outer end of said arm and passing a bolt 37 through said socket, suitably secured in such manner that the bolt may turn in the socket, and attaching to the lower end of the said bolt a horizontal collar 38, in which collar a tube 39 is mounted to slide, carrying the chalk 40 at its outer end, the said tube being provided with a follower the equivalent of that shown in Fig. 2. It will be observed that under this construction, the tube 39, carrying the chalk 40, is vertically adjustable, is horizontally adjustable, and is also laterally adjustable, all the adjustments being the same as under the construction shown in Figs. 1, 2, and 3.

In Figs. 5 and 6 another slight departure is illustrated, wherein a sleeve 41 is employed to slide upon the scale-arm *b'* of the measuring-bar B. This sleeve 41 is exteriorly circular and is held to the said scale-arm *b'* by a set-screw 41^a of any approved type. The interior of the sleeve 41 is provided with a rectangular bore 42, so as to fit over the aforesaid scale-arm *b'*. At the exterior of the sleeve 41 an annular recess 43 is produced, and in this recess a band 44 is fitted to turn.

The said band 44 is connected in any suitable or approved manner with a horizontal tube 45, open at both ends, and in this tube 45 a second tube, 46, is mounted to slide, its outer end being constructed to clamp a chalk 47. A follower 48 is located in the said inner tube, adapted to feed the chalk 47 outward as used, said follower 48 corresponding to the followers described with reference to the other forms of the device.

It will be observed that this device is exceedingly effective and is capable of three movements—a vertical movement, a horizontal movement, and a movement at an angle to the scale-arm of the measuring-bar—and that under all conditions of construction the operator will have the device under complete control and will be enabled to cause the marking-chalk to make a mark more or less decided and to accommodate the marking-arm to any irregularities in the garment to be marked. Further, in the event a skirt is to be marked for the purpose of shortening the skirt or turning up a hem the line marking the skirt will be perfect throughout the diameter of the skirt, thus bringing the entire bottom edge of the skirt at practically the same distance from the ground. Furthermore, by marking the skirt as described a line of trimming may be placed uniformly on the skirt.

Having thus described our invention, we claim as new and desire to secure by Letters Patent—

1. In a marking device for garments, a stand, a measuring-bar revolvably connected with the stand and having an upright scale member, a slide adjustable upon said scale member of the measuring-bar, a guide-arm at an angle to the said scale member, a pivotal connection between the guide-arm and slide, and a marking-arm adjustably supported upon the guide-arm.

2. In a marking device for garments, a stand, a measuring-bar revolvably connected with the stand, a guide-arm having lateral and vertical adjustment upon the measuring-bar, and a marking-arm carried by and adjustable upon the guide-arm.

3. In a device for marking garments, a stand, a measuring-bar revolvably and adjustably connected with the stand, a guide-arm adjustable on the measuring-bar, means for securing the guide-arm in position on the measuring-bar, the guide-arm having pivotal connection relative to the measuring-bar, and a marking-arm having sliding and adjustable connection with the guide-arm.

4. In a device for marking or gaging garments, a platform, a measuring-bar including a vertical scale-arm and a horizontal arm, the latter arm being adjustably and revolvably connected with the stand, a sleeve mounted to

slide on the scale-arm, means for securing the said sleeve in position on the said scale-arm, a guide-arm having a pivotal connection with the said sleeve, a block mounted to slide on the guide-arm, a marking-arm adjustably connected with the said block, a bearing for the marking-arm connected with the said sleeve, and means for holding a marking device at the end of the marking-arm.

10 5. In a device for gaging or marking garments, a platform, a measuring-bar comprising a vertical scale-arm and a horizontal base-arm, the base-arm being adjustably and revolvably connected with the said platform, a sleeve

mounted on the scale-arm, means for holding the said sleeve in adjusted position, a guide-arm connected with the said sleeve, and a marking-arm having guided movement relative to the guide-arm and pivotal relation to the scale-arm.

In testimony whereof we have signed our names to this specification in the presence of two subscribing witnesses.

ALBERT WATERMAN.
RUDOLF WATERMAN.
